UNITED STATES PATENT OFFICE.

CHARLES C. ARMSTRONG, OF HUNTINGTON, WEST VIRGINIA.

DESIGN FOR A COOKING RANGE.

Application filed November 9, 1925. Serial No. 15,386. Term of patent 14 years.

To all whom it may concern:

Be it known that I, CHARLES C. ARMSTRONG, a citizen of the United States, residing at Huntington, in the county of Cabell and State of West Virginia, have invented a new, original, and ornamental Design for Cooking Ranges, of which the following is a specification, reference being had to the ac-

companying drawing, forming part thereof.

Fig. 1 is a perspective view of the design.

Fig. 2 is a perspective view from another view point.

I claim:

The ornamental design for a cooking range, as shown.

CHARLES C. ARMSTRONG.
